UNITED STATES PATENT OFFICE.

JOSEPH F. JOY, OF BELLE VERNON, PENNSYLVANIA.

COAL-WINNING DEVICE.

1,273,869

Specification of Letters Patent. Patented July 30, 1918.

Application filed September 22, 1917. Serial No. 192,773.

To all whom it may concern:

Be it known that I, JOSEPH F. JOY, a citizen of the United States of America, residing at Belle Vernon, in the county of 5 Fayette and State of Pennsylvania, have invented certain new and useful Improvements in Coal-Winning Devices, of which the following is a specification.

This invention relates to certain new and 10 useful improvements in coal winning devices and has among its objects a device of its kind which is simple in construction and effective in operation.

Prior to my invention it has been customary in winning coal to break the same down from the face of a vein by the use of multi-part wedges, mechanical picks or a blast of dynamite. The first is seldom fully effective and the use thereof requires a large 15 amount of labor and time as a hole must first be drilled into the vein of sufficient size to receive the wedge and after the wedge is inserted in this hole the same is expanded. Necessarily, the wedge has to be of superior 20 quality to undergo the strains incident to its use and considerable power is necessary to expand the same. The mechanical picks are undesirable mainly in view of their bulky 25 nature and the fact that their use produces a large quantity of fine coal and dust. Explosives are not desirable for this purpose in view of the danger incident to their use and doubly so in view of the fact that the 30 same is not effective unless a large quantity thereof is used for each blast. Further, it is an acknowledged fact that excessive and 35 reckless use of explosives are attendant with many hazards and are the cause of more or less disastrous mine fires and explosions.

Also the use thereof greatly reduce the value 40 of the coal and produces a great quantity of fine coal and dust.

The primary object of my invention is to overcome the above defects and to this end 45 includes a tapering screw which is adapted to be turned into the face of a vein until the coal is broken down to a depth approximately equal to the depth of a previously made overcut or undercut. Thus, in this 50 invention, a simultaneous twisting or turning and thrust movement of the breaking down or wedge element occurs by turning the same, and, in view of the threads directly engaging the material being wedged or

broken down, more effective results are produced and the wedging or breaking down element is constructed of a fewer number of parts which are more durable and stronger than those of prior devices for this purpose. By my invention the coal is broken down in 55 the most desirable sizes with a minimum reduction of its value and production of fine coal and dust, in which state it may be easily loaded into cars and removed from the mine.

A further object is to so construct the 60 present device that a drill may simultaneously act in advance of the wedging element to produce a relatively small hole in the vein in order that the wedging element may easily advance, engage the coal and screw 65 thereinto to break it down.

A still further object is to provide means whereby the drill may be rotated at a greater speed than the wedging element to thereby produce a hole entirely clear of obstructions 70 in advance of the wedging element, the same being an aid to the speed and effectiveness with which the said element performs its function.

With these general objects in view and 75 others that will appear as the nature of the invention is better understood, the same consists in the novel structure, combination and arrangement of parts hereinafter fully described, illustrated in the accompanying 80 drawings and set forth in the appended claims.

In the drawings like characters of reference indicate similar parts throughout the 85 several views, and

Figure 1 is a plan view of one embodiment 90 of my invention and illustrating the position of the same when in operation in the mine room.

Fig. 2 is an enlarged detail view, partly in 95 horizontal longitudinal section of a portion of the structure shown in Fig. 1.

Fig. 3 is a rear end elevational view of the device shown in Fig. 2.

Fig. 4 is a side elevational view of the 100 gear casing.

Fig. 5 is a side elevational view of the device, partly in vertical section, illustrating a modified form of gearing for the drill and wedging element.

Fig. 6 is a plan view showing the gearing 105 shown in Fig. 5.

Fig. 7 is a side elevational view showing

another embodiment of the invention and illustrating the position of the same when in operation in the mine room, where the over-cutting system of mining is used, and 5 Fig. 8 is a plan view showing the application of my invention when mining is accomplished by the "loop-cutter" of U. S. Patent No. 600,838 to G. F. Meyers.

Referring to the form of the invention 10 illustrated in Figs. 1 to 4 inclusive, 5 indicates the mine room which is provided with the usual tracks or rails 6 and upon these rails rest the wheels 7 of a truck 8 which has a suitable motor 9 secured thereon. The 15 shaft 10 of this motor is flexibly connected by universal joints 11 and shaft section 12 to the shank 13 of the coal drill 14. The male members of universal joints 15 are suitably supported from the truck 8 and these 20 joints are connected by rods 16 to the universal joints 17, one member 18 of each being carried by the gear casing 19. It will be seen that this construction allows a universal movement of the casing 19 and associated parts relative to the truck, but at the 25 same time prevents rotation of casing 19. Journaled in and extending through the hub 20 of the casing 19 is the hollow shank 21 of the hollow tapering frusto-conical externally 30 threaded wedging or breaking down element 22. The shank 13 is journaled in and extends through the shank 21 to a point where said shank 21 is provided with an enlargement 23 apertured as at 24 to form an exit 35 for material removed by the drill 14 which extends through the element 22 and beyond the small end thereof. Secured upon the shank 13 adjacent one end thereof and within the casing 19 is a spur gear 25 which 40 meshes with a plurality of spur gears 26 each of which in turn mesh with the internal rack 27 of the casing 19. The gears 26 are journaled upon pins 28 projecting from the arms 29 of the spider 30 which is splined to shank 45 21 and journaled in hub 20.

In the operation of this form of the invention, the face of the vein is undercut as usual, as outlined by dotted line Fig. 1, and then the tool is directed to the vein approximately at the point shown in Fig. 1. The 50 motor 19 is then started and rotation is thus imparted to the drill 14 at the same speed as that of the motor shaft, while the element 22 is rotated at a lower speed, it being noted that the gear 25 rotates gears 26 about the pins 28 and in view of the fact that casing 19 is held from rotation and that gears 26 mesh with rack 27 of casing 19 said 55 gears 26 will bodily move around the gear 25 thus rotating spider 30, shank 21 and element 22. The drill 14 first forms a hole which is then entered by the small end of the element 22 and the further screwing of this element, due to its tapering form and thread-

ed engagement with the coal, causes the coal 65 to be torn away and broken down. This operation is repeated at the point indicated by dotted lines at 31 and 32, if necessary to break the coal down across the entire working face. 70

Referring to Figs. 5 and 6 it will be noted that the differing speeds of rotation may be imparted to the drill 14 and element 22 by gearing other than the planetary gearing hereinbefore described. In these figures the 75 motor or power shaft 33 has a bevel gear 34 secured thereon, and this gear meshes with another bevel gear 35 secured upon the end of the drill shank 13. Upon the shaft 33 and spaced from gear 34 is also secured a 80 sprocket wheel 36 around which passes an endless sprocket chain 37 which also passes around a sprocket wheel 38 secured upon a suitably supported and rotatable shaft 39. Secured upon the shaft 39 is a worm 85 40 which meshes with a worm gear 41 carried by the shank 21 of the wedging element 22. It is obvious that when rotation is imparted to shaft 33 the drill 14 will be driven faster than the element 22 by this gearing. 90

In Fig. 7 a portable outfit is shown wherein the motor 9 and casing 19 are secured to a base 42 and the motor shaft 10 is connected directly to the auger 14 while the planetary gearing shown in Figs. 2 and 3 is contained 95 by this casing. In the use of this form of the invention the face of the vein is overcut as at 43 and the operation is substantially the same as that of the form shown in Figs. 1 to 4 inclusive. 100

In the cases where a mining machine is used having a "loop-cutter" similar to that shown in U. S. Patent No. 600,838 to G. F. Meyers, the drill 14 is not necessary in view of the space formed by the cutter 46 as illustrated in Fig. 8. In this use of the device, the member 21, 22, and 41 of Fig. 5 may be employed by simply discarding the drill. In this figure the wedging element 22 is rotated through suitable gearing 44 between 110 the shank 21 and power shaft 45. Thus it will be seen that my device is a valuable adjunct to this type of machine and if mounted and operated to follow the cutter it would break the coal away in a desirable size and 115 expedite the mining operation. 120

While the forms of the invention herein shown and described are those which are believed to be the preferred embodiments thereof, it is nevertheless to be understood that minor changes may be made therein without departing from the spirit and scope of the invention as claimed. 125

What I claim as new is:—

1. A coal winning device including an element substantially in the form of a cone having threads on its outer surface to engage the coal being broken down, means for

- 5 screwing said cone with its small end in advance into said coal, and means operating in advance of said element to form a hole in the coal of a larger diameter than that of the small end of said element.
2. A coal winning device including a wedging element threaded to screw into coal with its small end in advance, a shaft applied to said wedging element by which the latter is adapted to be turned, and means operating in advance of said element to form a hole in the coal of a larger diameter than that of the small end of said element.
- 10 3. A coal winning device including a wedging element threaded to screw into coal with its small end in advance, a shaft applied to said wedging element by which the latter is adapted to be turned, means for turning said shaft, and means operating in advance of said element to form a hole in the coal of a larger diameter than that of the small end of said element.
- 15 4. A coal winning device including a shaft having a threaded substantially cone-shaped wedging element upon one end adapted to be screwed into coal with its small end in advance, and means operating in advance of said element to form a hole in the coal of a larger diameter than that of the small end of said element.
- 20 5. A coal winning device including a threaded substantially cone-shaped wedging element adapted to be screwed into coal with its small end in advance, and means operating in advance of said element to form a hole in the coal of a larger diameter than that of the small end of said element.
- 25 6. A coal winning device including an element substantially in the form of a cone having threads on its outer surface to engage the coal being broken down, means for screwing said cone with its small end in advance into said coal, a drill operating in advance of said element to form a hole in the coal of a smaller diameter than that of the large end of said element, and means for rotating said element and said drill respectively at differing speeds.
- 30 7. A coal winning device including a wedging element threaded to screw into coal with its small end in advance, a shaft applied to said wedging element by which the latter is adapted to be turned, a drill operating in advance of said element to form a hole in the coal of a smaller diameter than that of the large end of said element, and means for rotating said element and said drill respectively at differing speeds.
- 35 8. A coal winning device including a shaft having a threaded substantially cone shaped wedging element upon one end adapted to be screwed into coal with its small end in advance, a drill operating in advance of said element to form a hole in the coal of a larger diameter than that of the small end of said element.
- 40 9. A coal winning device including a threaded substantially cone-shaped wedging element adapted to be screwed into coal with its small end in advance, a drill operating in advance of said element to form a hole in the coal of a larger diameter than that of the large end of said element, and means for rotating said element and said drill simultaneously at differing speeds.
- 45 10. A coal winning device including a threaded substantially cone-shaped wedging element adapted to be screwed into coal with its small end in advance, a drill operating in advance of said element to form a hole in the coal of smaller diameter than that of the large end of said element, and means for rotating said element and said drill whereby the drill is rotated at a faster speed than said element.
- 50 11. A coal winning device including a support, a motor mounted on said support, a tapered rotatable wedging element, and a flexible driving connection between said motor and said element.
- 55 12. A coal winning device including a support, a motor mounted on said support, a threaded substantially cone-shaped rotatable wedging element adapted to be screwed into coal with its small end in advance, and a flexible driving connection between said motor and said element.
- 60 13. A coal winning device including a threaded substantially cone-shaped rotatable wedging element adapted to be screwed into coal with its small end in advance, a drill extending through and beyond the small end of said element and means to rotate said element and said drill.
- 65 14. A coal winning device including a threaded substantially cone-shaped rotatable wedging element adapted to be screwed into coal with its small end in advance, a drill extending through and beyond the small end of said element, and means to rotate said element and said drill respectively at different speeds.
- 70 15. A coal winning device including a threaded substantially cone-shaped rotatable wedging element adapted to be screwed into coal with its small end in advance, a drill extending through and beyond the small end of said element, and means to rotate said element and said drill whereby said drill is driven faster than said element.
- 75 16. A coal winning device including a support, a planetary gearing including a casing, means connected to said support for holding said casing from rotation, a drill carried by the shaft of said gearing, a threaded substantially cone-shaped wedging element con-

nected to the spider of said gearing, and means to rotate said drill carrying shaft.

17. A coal winning device including a planetary gearing having a casing, means to hold said casing from rotation, a threaded substantially cone-shaped wedging element connected to the spider of said gearing, a drill carried by the shaft of said gearing and extending through and beyond the small end of said element, and means to rotate the drill carrying shaft.

18. A coal winning device including a support, a planetary gearing having a casing, a flexible connection between said support and said casing to hold the latter from turning, a threaded substantially cone-shaped wedging element connected to the spider of said gearing, a drill carried by the shaft of said gearing and extending through and beyond the small end of said element, a motor mounted on said support, and a flexible driving connection between said drill carrying shaft and said motor.

19. A coal winning device including a planetary gearing having a casing, means to hold said casing from rotation, a threaded substantially cone-shaped wedging element having a shank connected to the spider of said gearing, a drill carried by the shaft of said gearing and extending through and beyond the small end of said element, an opening in the shank of said element forming an exit for the material removed by said drill, and means to rotate the drill carrying shaft.

35 20. In a coal winning device, the combination of a threaded substantially cone-shaped wedging element adapted to be screwed into the coal being split with its small end in advance, of means associated

with said element to form a clearance space 40 in said coal whereby the small end of said element may readily enter the said coal.

21. A splitting device including a tapering wedging element adapted to be forced by a continuous feeding action into the material being split with its small end in advance, and means associated with said element to continuously move therewith simultaneously and at the same rate of speed into said material and operating in advance of 50 said element to form a hole in the material being split of a larger size than that of the small end of said element.

22. A splitting device including a threaded substantially cone-shaped wedging element adapted to be screwed into the material being split with its small end in advance, and a drill extending forwardly from the small end of said element and adapted to form a hole in the material being split 60 whereby the small end of said element may readily enter said material.

23. A wedging member for coal winning devices comprising a threaded substantially cone-shaped rotatable element having an 65 operating shank, said shank and said element being provided with an axial longitudinal bore.

24. A wedging member for coal winning devices comprising a threaded substantially 70 cone-shaped rotatable element having an operating shank, said shank and said element being provided with an axial longitudinal bore adapted to receive a drill, and said shank being provided with a transverse 75 slot to form a drillings exit.

In testimony whereof I affix my signature.
JOSEPH F. JOY.
